UNITED STATES PATENT OFFICE.

PETER A. SIMMONS AND CHARLES J. HENRY, OF LEADVILLE, COLORADO.

ORE-CONCENTRATOR.

SPECIFICATION forming part of Letters Patent No. 289,152, dated November 27, 1883.

Application filed June 9, 1883. (No model.)

To all whom it may concern:

Be it known that we, PETER A. SIMMONS and CHAS. J. HENRY, citizens of the United States of America, residing at Leadville, in the county of Lake and State of Colorado, have invented certain new and useful Improvements in Ore-Concentrators, of which the following is a specification, reference being had therein to the accompanying drawings.

10 This invention pertains to improvements in ore-concentrators, having for its object to effectually and thoroughly remove gangue from metalliferous ore; and it consists of apparatus for carrying out these ends, substantially as hereinafter fully set forth and claimed.

15 In the accompanying drawings, Figure 1 is a plan view of our invention. Fig. 2 is a longitudinal vertical section thereof, taken on the line *x x*, Fig. 1, and Fig. 3 is a side elevation 20 of the same; Figs. 4, 5, and 6, detail views. Fig. 7 is an enlarged detail, in plan, of the lower end of the machine. Fig. 8 is a transverse section on line *y y*, Fig. 1, in a plane perpendicular to the general plane of the frame; and Fig. 9 is a longitudinal vertical section 25 through the center of the two lowermost pans of one series.

30 A designates a frame-work, which, for the purposes of this invention, is constructed longitudinally on either side (see Fig. 2) with inclined timbers *a a*, and above these with a single inclined timber, *a'*, Fig. 2, arranged at about its center.

35 B are two long rectangular frames, supported in an inclined position upon flexible uprights or bars *b b*, connected thereto and to the inclined timbers *a a* of the frame A, to allow said frame to have lateral vibratory motion, the purpose of which will appear hereinafter. The means of connection between 40 said bars *b* and the frames and the beams consist, preferably, of four horizontal pivotal rods, C, on either side of the frame, one for each of the points of attachment of the 45 ends of bars *b*. (See Fig. 2.) These pivotal rods C are supported, the lower ones in the lower middle inclined beams, *a*, and the upper ones in the inclined rectangular frames B B. These frames are rigidly connected together by cross-pieces *d*, located at either 50 end, and at intervals beneath the plates e.

Their side pieces or bars are grooved longitudinally on the inside to receive a series of plates, *e*, which have affixed to them socketed pieces or bearings *e'*, whose upper surfaces 55 are of not so great an inclination as that of the plates *e*, which bearings receive the axes *f*, upon which the pans D are mounted and secured. The plates *e* are adapted to be held, respectively, by means of pawls *e'*, pivoted to 60 the sides of the frames B B and engaging with stops or projections *e''* on said plates. As shown in Fig. 7, this arrangement permits of the independent holding of any one of the plates, with its pan, hereinafter described, while the 65 adjacent upper pan is being, and after having been, removed, as is required in shifting the pans from one point to another during the concentrating process. Beneath the plates of the lowermost pans of the two frames are two 70 slides, *g g*, with their side edges adapted to fit and move in longitudinal grooves *g'*, Figs. 6 and 8, in the said frames, and with their lower edges, *g''*, Fig. 7, bent or turned up to hold the lowermost plates from sliding out of their 75 grooves and out of the frames, these slides themselves being held in their grooves by straps *h*, connected thereto, and to a common shaft, E, around which they are wound, said shaft being suitably journaled in the lower inclined beams, *a*, of the frame A. The shaft E is provided with cranks *E'* and ratchets *E''*, 80 which engage pawls *E'''*, hung on the sides of the outer inclined beams, *a*, of frame A. The pans D are arranged, it will be observed, successively one in a lower or higher plane than the other, or in a "stair-step" manner, the uppermost ones of which we style the "cleaning" pans, and those next to these the "feed" 85 pans, while all the rest we style the "concentrating" pans. To the axes or shafts of the pans are fixed cogged or toothed disks *D'*, Figs. 4 and 7, which are adapted to be engaged by pawls *F'* to give the pans an intermittent rotary motion, as presently described, said 90 pawls being held in engagement with the cogged disks of the pans by springs *F''*, and which pawls and springs are attached to a longitudinally-reciprocating frame, G, presently described.

95 F³, Fig. 7, are springs actuating retaining-pawls *F*, which act in the toothed disks 100

D', Fig. 4, and hold the pans as against reaction when said pans are released from the actuating-pawl F', these springs and pawls being secured in suitable apertures provided in the 5 sides of the frame B.

G' is a transverse shaft, suitably journaled at the upper end of the frame A, in two posts or uprights thereof, and to which is applied a fixed driving-pulley, G'', and a loose pulley, 10 G', and a beveled pinion, H, with which pinion engages the corresponding pinion, J, on the upper end of an inclined shaft, K, supported in blocks or bearings i, secured upon the upper inclined beam, a', of the frame A. The 15 shaft K carries cams j j, which, as it is revolved by the driving-shaft G', strike against projections k' k' on the opposite sides of the frames B, and beneath frame G, between which frames B the shaft K is arranged, and thereby 20 imparts to the said frames, with their superposed pans, a laterally vibratory motion, to facilitate the precipitation of the ore and friction, while the gangue or impurities are carried off by the overflow of the water from the pans. 25 Synchronal with this movement of the said parts, the frame G, carrying actuating-pawl F, Fig. 7, is subjected to a longitudinally-reciprocating motion, whereby the pans receive an intermittent rotary motion to more 30 thoroughly agitate and concentrate the precious metal by the following mechanism:

Upon the shaft G' is an eccentric, l, which actuates a rod or pitman, L, Fig. 2, connected to a crank-shaft, M, suitably journaled in uprights of the frame A. One end of this shaft is connected by a crank-arm, m, to a rod, n, which has at its inner end a cross-bar, o, connected to parallel upright levers p, fulcrumed at the opposite inner sides of the frames B at 40 N', Fig. 2, and pivoted to frame G by means of cross-bar p'. The upper ends of these levers are connected to and vibrate, with longitudinally-reciprocating motion, the frame G, carrying the pan-actuating pawls F'. The 45 frames B are held in position upon frame A by rods q, connected to the same, as shown in Fig. 1, partly in dotted lines, and Fig. 9. The crank-arm m, Fig. 2, has a series of adjusting-apertures, whereby the vibratory movement 50 of the frame G, carrying the actuating-pawl of the pans, may be varied to vary the intermittent rotary motion of the pans, as may be required. Frame G consists of two longitudinal bars, Y Y, and two transverse bars, Y', Fig. 1, resting upon the inner longitudinal bars of frames B, and it is secured and oscillated thereon by means of the levers p, Fig. 2, which project on the inner side and above the frames B, and are pivoted to frame G. 55

60 Rubber or elastic cushions or buffers rr are secured to frame B, beneath the frame G, to prevent the too sudden collision of the frames B with the blocks or bearings i, and hence the sudden jarring of the pans, while permitting 65 them to have sufficient jar for the proper agitation and concentration of the precious metals or ore.

It will be seen that with the ore or precious metals placed in the feed-pans next to the topmost or cleaning pans in a comminuted state, water being poured therein upon the ore, and this operation being continued, the water will float off the gangue or impurities from these pans into the pans next below—the concentrating-pans—which will also catch any light particles of precious metals or ore that may have overflowed with the impurities, which process will continue on down with all the pans. While this is taking place the intermittent rotary motion of the pans and the laterally-vibratory motion transmitted thereto from the laterally-vibratory frame, together with the jarring, will cause the thorough concentration of the ore or precious metals. The topmost pans can be removed at the desired stage of the process, and the pans next below moved into their place by turning the shaft E, that operates the belt h, that moves the slides g g, arranged under the lowermost pans. After this the previously lowermost pan-supporting plates can be retained at their point of elevation by means of pawls e' and stops e'', above described, and the slide can then be dropped to its original position by slackening or unwinding the belt h, which will permit the previously uppermost removed pans to take the place of the previously lowermost pans. It is obvious that this operation can be kept up until the positions of all the pans have been successively shifted to enable the more effectual concentration of the ore in each pan. The comminuted ore, together with water, is fed, either by hand or automatic feeding machinery, into the second highest of a series of pans arranged in successive steps on an inclined plane, as aforesaid, wherein the relatively heavier metallic particles of the comminuted ore are caused to gravitate to the bottom, and the lighter particles to rise to the surface by the conjoint motions of the pans and the levigating action of the water, which causes the lighter portions of the ore to flow with the water from the second pan down into the third pan, where the continuous motions aforesaid cause a further settling of the heavier particles, while the lighter portions are made to rise to the surface and to flow from the third pan, and so continuously downward through the whole series of pans, in every one of which the relatively heavier particles are separated from the lighter ones in the same manner as hereinbefore described, until the material which flows out of the lowest pan is mostly deprived of all metallic particles. The next step in the process is removing the cleaning or uppermost 115 pan from the series and emptying it when the ore therein is sufficiently concentrated, and simultaneously moving upward one step on the inclined plane the remaining pans, and thus carrying the previous feed-pans into the position of the cleaning-pans and placing an empty pan at the lower end of the series. Thus the ore is successively more and more deprived of its lighter particles, the heavier remaining in 120 125 130

the pans, and thus the separation of the heavy metallic particles from the light gangue particles is effected.

Having thus fully described our invention, 5 we claim and desire to secure by Letters Patent—

1. In an ore-concentrator, the combination, with the pans having teeth or cogs, of the longitudinally-reciprocating frame provided with 10 pawls for imparting an intermittent rotary motion to the pans, substantially as and for the purpose set forth.

2. In an ore-concentrator, the pans having teeth or cogs, in combination with frame B, 15 provided with pawls for retaining the pans against reaction, and frame G, provided with pawls actuating the pans, substantially as and for the purpose set forth.

3. In an ore-concentrator, the pans having 20 teeth or cogs, and the frame supporting said pans, in combination with frame G, provided with pawls for actuating the said pans, pawls for retaining said pans against reaction, and mechanism for imparting a lateral jarring or 25 vibratory motion to the pan-supporting frame, substantially as and for the purpose set forth.

4. In an ore-concentrator, the combination, with pans, the pan-supporting frames, and means for flexibly supporting said frames, of 30 the shaft K, provided with cams adapted to operate said frames, elastic buffers arranged to modify the force of the collision of frames B and the blocks or bearings *i* of shaft K, substantially as and for the purpose set forth.

35 5. In an ore-concentrator, the combination

of the pans D, the longitudinally-grooved frames B, and the plates *e*, adapted to fit into said frames and support the pans D, substantially as and for the purpose set forth.

6. In an ore-concentrator, the combination, 40 with the frames B, provided with pawls, and the pans D, having teeth or cogs D', of the longitudinally-reciprocating frame G, provided with pawls engaging the teeth or cogs of the pans, and the driving mechanism, substantially 45 as and for the purpose set forth.

7. In an ore-concentrator, the pan-supporting plates, the pans, and the longitudinally-slotted frames, in combination with the slides having upturned lower edges, the shafts, and 50 belts, said belts being connected to said slides and said shafts, substantially as and for the purpose set forth.

8. In an ore-concentrator, the combination 55 of the pans and the pan-supporting frames B, provided with slots, grooves, and pawls, the pan-supporting plates *e*, adapted to move in the grooves and provided with projections or stops engaged by said pawls, the slide *g*, having an upturned edge, and the slide-adjusting 60 mechanism, substantially as shown and described.

In testimony whereof we affix our signatures in presence of two witnesses.

PETER A. SIMMONS.
CHARLES J. HENRY.
